UNITED STATES PATENT OFFICE

TORCUATO DI TELLA, OF BUENOS AIRES, ARGENTINA

LIQUID-DISPENSING APPARATUS

Application filed April 4, 1928, Serial No. 267,422, and in Great Britain January 30, 1928.

This invention relates to apparatus for dispensing liquids in predetermined quantity, and is designed primarily for installation in gasoline filling stations, though it can, of course, be used in various other connections.

According to the invention, which is based on the theory of non-compressibility of liquids, a dispensing or measuring chamber or vessel is provided, connected to be fed with liquid from a main source of supply and equipped with a discharge or outlet valve having a handle for opening and closing it. This chamber contains an overflow device which is so positioned that the liquid commences to pass therethrough so soon as a quantity in excess of that to be dispensed is delivered to the chamber. The excess liquid is returned to the source of supply, but a part of it flows into and fills an auxiliary receptacle or chamber provided with a movable controller which is connected to the valve handle (the latter normally occupying a position corresponding to the closed position of the valve), so that a hydraulic lock is thereby formed which prevents the valve from being opened until the dispensing chamber contains only the precise quantity of liquid to be discharged, whereafter the lock chamber is emptied automatically and the handle unlocked and actuated. Further and more detailed description will be given subsequently.

In the accompanying drawing:

Figures 1 and 2 are vertical sectional views of a preferred embodiment of the invention, showing the outlet valve and associated parts in locked and unlocked (i. e., closed and open) positions, respectively; and

Figs. 3 and 4 are detailed sections, on an enlarged scale, of a slightly modified arrangement and likewise showing the outlet valve and associated parts in closed and open positions.

Referring more particularly to the drawing, 1 indicates a tank or reservoir constituting the main source of supply of the gasoline or other liquid to be dispensed in measured quantity, and 2 the dispensing vessel or chamber; these two receptacles be-

ing connected by a vertical delivery pipe 3 which extends from a point close to the bottom of receptacle 1 through and slightly above the bottom of receptacle 2. A pump 4 of any suitable character is fitted in the delivery pipe and may be operated in any desired manner; manually, for example, as in the construction illustrated. From the dispensing chamber or vessel projects a discharge pipe 5, having included in it an outlet valve 6, here shown as of the rotary plug type, which is opened or closed by means of a handle or lever 7 secured to one end thereof; and this valve, as will be understood, normally occupies a closed position.

Operation of the pump will result, therefore, in the delivery of liquid through pipe 3 from the supply tank 1 to the dispensing vessel 2, the latter being preferably made transparent so that the progress of its filling can be watched. When the precise quantity of liquid to be dispensed has been supplied, the actuation of the pump ceases and any liquid in excess of that quantity is returned to tank 1, this being effected by means of a combined overflow and return pipe. The upper section 8 of said pipe projects vertically through the bottom of vessel 2 to the exact height of the liquid level for the quantity in question, while its lower section 9, which is offset from the upper section by the fitting 10, opens into tank 1, as shown.

Under ordinary conditions, it would be possible to open the outlet valve 6 and thus draw off the contents of the dispensing vessel 2 before all the excess liquid therein has returned to tank 1, in which event a quantity of liquid greater than that to be purchased would be discharged. To prevent this—and, in the interest of the purchaser, to prevent also a premature opening of the valve, with resultant short measure—the hydraulic lock previously mentioned is employed. This lock, in the construction illustrated, comprises an auxiliary chamber or receptacle 11, in the form of a cylinder, connected by a short vertical pipe 12 to the fitting 10 in line with pipe 8, and by a second short pipe 13 of smaller diameter with pipe 9; the pipes 12 and 13 opening through the top and bot-

tom of the cylinder at points 14 and 15 which, in the present instance, are represented as diametrically opposite, though that arrangement is not essential. Hence, some 5 of the excess liquid passing through the overflow pipe 8 will escape by way of pipe 12 into the cylinder 11 and will fill the same rapidly, since the outlet or drain pipe 13, because of its smaller diameter, insures a 10 slow emptying action.

The piston 16 working in said cylinder constitutes a controller for the lock, as well as for the filling operation, and has its stem projecting outward through the inner cylinder head and connected at its free end to the central part of valve lever 7 by a pin-and-slot joint 17 or similar loose connection. In consequence, both the outlet valve 6 and the piston or controller 16 will be operated 15 simultaneously by a movement of lever 7, the piston moving forward while the valve turns toward open position; but if such movement of the piston is blocked in any way as, for instance, by the liquid in front 20 of it, then the lever 7 cannot be operated and the valve will be held or locked in closed position. Moreover, as soon as the piston starts its forward movement, it closes the ports 14 and 15, thus shutting off the supply 25 of liquid to the cylinder and trapping the liquid already therein, which will have the effect of resisting further movement of the piston.

To avoid the formation of air locks, a 30 venting device is provided in connection with the cylinder which is initially open, so as to exhaust the air as the cylinder fills, and ultimately closes. This device may comprise, as shown, a casing 18 mounted 35 upon the upper or outer end of the cylinder and communicating with the interior thereof by way of a hollow stem or nipple 19; said cylinder occupying an inclined position. Casing 18 contains a freely-movable or 40 floating member 20 carrying a pointed projection 21 that is designed to close the lower or inner end of a vent pipe 22 when the float is lifted; said float normally occupying its 45 lowered position within the casing but being raised slightly above the bottom of the casing, as by an apertured part or spider 23 to enable the escape of air around it from the cylinder. Additional air ports may, however, be provided if desired.

The operation is substantially as follows: 50 Actuation of pump 4 will deliver the liquid to the dispensing vessel 2, which will gradually fill, the normally-closed valve 6 preventing its escape. When the level of the liquid rises above pipe 8, which can be ascertained by watching the filling operation, the pumping action is discontinued, and the excess liquid in vessel 2 then overflows through pipes 8 and 9 and returns to tank 1. Part 55 of this liquid escapes through pipe 12 and

port 14 into the lock cylinder 11 and rapidly fills the same, the liquid forcing out the air ahead of it and finally making its way through nipple 19 into casing 18, where it raises valve 20 into closed position, thus trapping the liquid in the cylinder. When this occurs, the piston 16 which forms the controller of the hydraulic lock will be held against operation, so that the outlet or dispensing valve 6 cannot be opened. The 60 cylinder is then allowed to drain slowly through port 15 and pipe 13 into return pipe 9, and at the conclusion of this operation lever 7 is actuated to rotate the dispensing valve into open position, thereby discharging the contents of vessel 2. The float valve 20 returns to its lower position as the cylinder 11 empties, and finally lever 7 is actuated to re-close valve 6.

The modified arrangement shown in Figs. 3 and 4 embodies, in the main, the same parts as the first form and operates in substantially the same way, excepting, however, that the outlet valve is locked in open position so that it cannot be closed to cut off the flow until the entire amount of liquid to be dispensed has been discharged from the dispensing vessel 2'. In this form, the dispensing vessel 2', which may be filled in any desired way, is equipped with a depending discharge pipe 5' in which the outlet valve 6 is located. The cylinder 11 is equipped, as before, with a piston 16 and an associated venting device; but the supply and discharge pipes 12' and 13' for the cylinder are connected directly to pipe 5' and at points located below valve 6, these pipes communicating with the cylinder by way of the cylinder ports 14' and 15'.

The valve 6 can therefore be turned or rotated into open position at any time from its normal closed position illustrated in Fig. 3, by means of its handle or lever 7, thereby moving piston 16 to the right. This puts the cylinder in communication with vessel 2', the liquid from which is then free to flow through pipe 5', some of it escaping through pipe 12' into the cylinder and filling the same with the result that the piston and, hence, the valve are locked in actuated position and cannot be operated until the cylinder has emptied.

I claim as my invention:—

1. Liquid dispensing apparatus, comprising a dispensing chamber provided with an outlet valve; a lever for operating the valve; a cylinder; a piston working therein and connected to said lever; and means for supplying a motive agent to the cylinder when the level of the liquid in the chamber rises above a predetermined level, thereby to lock said piston and lever against movement.

2. In combination, a liquid dispensing chamber; a discharge pipe leading therefrom; an outlet valve in said pipe; a valve-

operating member; a piston connected to said member; a cylinder wherein said piston works; and means for supplying liquid from said chamber to the cylinder to control the activity of the piston.

3. Liquid dispensing apparatus, comprising a dispensing chamber provided with an outlet valve and with an overflow; a hydraulic locking device for said valve embodying a cylinder, and a piston movable in the cylinder and connected with the valve; and a connection between the lock cylinder and the overflow for supplying overflowing liquid to said cylinder to lock the piston against movement.

4. Liquid dispensing apparatus, comprising a dispensing chamber provided with an outlet valve; means for operating the valve; a cylinder provided with inlet and outlet ports; a piston working in the cylinder and connected with the valve-operating means; means for supplying a motive agent to the inlet port of the cylinder when the level of the liquid in the chamber rises above a predetermined height, thereby to lock said piston and valve-operating means against movement; and venting means for the cylinder connected to the outlet port thereof.

5. Liquid dispensing apparatus, comprising a dispensing chamber; a discharge pipe leading therefrom; an outlet valve in said pipe; a valve-operating member; a piston connected to said member; a cylinder wherein said piston works having an inlet port and an outlet port; and piping leading to and from said inlet and outlet ports, respectively, to supply liquid from said chamber to the cylinder to control the activity of the piston, and to subsequently vent said cylinder.

6. Liquid dispensing apparatus, comprising a dispensing chamber; an outlet valve associated therewith; a handle for actuating said valve; and a hydraulic lock for said valve embodying a cylinder to receive liquid, and a piston movable in said cylinder and connected with said handle, said piston being normally held against movement by the liquid in the cylinder.

50 7. Liquid dispensing apparatus, comprising a dispensing chamber provided with an outlet valve and with an overflow; a valve-operating member; a hydraulic lock for said valve embodying a cylinder to receive liquid, and a piston movable in said cylinder and connected with said member; and a connection between said cylinder and the overflow for supplying overflowing liquid to the cylinder to lock the piston against movement.

60 8. Liquid dispensing apparatus according to claim 7, in which means is provided to vent the lock cylinder and thereby unlock the piston.

9. Liquid dispensing apparatus, comprising a dispensing chamber provided with an

outlet valve; a member for operating said valve; a lock cylinder provided with an inlet port and a vent; means for supplying liquid to said inlet to fill the cylinder; and a piston movable in said cylinder and normally locked against movement by the liquid therein, said piston being connected to said operating member to actuate the same.

In testimony whereof I affix my signature.
